CLAIM

The ornamental design for the light bulb changer head, as shown and described.

DESCRIPTION

FIG. 1 is a perspective view of a light bulb changer head in accordance with a first embodiment of the present invention; FIG. 2 is a side elevational view of the light bulb changer head illustrated in FIG. 1;

FIG. 3 is a top plan view of the light bulb changer head illustrated in FIG. 1; and,

FIG. 4 is a bottom plan view of the light bulb changer head illustrated in FIG. 1.

The broken lines depict portions of the light bulb changer head in which the design is embodied that are not considered part of the claimed design.

1 Claim, 4 Drawing Sheets(56)
